DETECTING AND EJECTING MEANS FOR
PACKING STRIP APPLYING MACHINES

Paul E. Pearson, Chicago, Ill., assignor to Continental Can Company, Inc., New York, N. Y., a corporation of New York

Original application December 27, 1940, Serial No. 371,974. Divided and this application November 16, 1942, Serial No. 465,764

17 Claims. (Cl. 113—7)

1

The invention relates generally to the manufacture of metallic containers having solderless side seams wherein non-metallic packing strips are included, and it primarily seeks to provide, in combination with apparatus for applying said packing strips, novel means for detecting and ejecting all such sheets or body blanks as are devoid of packing strips after having passed through the packing strip applying means or before they are passed on to mechanisms for completing the formation of the container bodies.

In my U. S. Letters Patent 2,319,825, issued on May 25, 1943, there is disclosed and claimed apparatus for forming packing strips and adhesively attaching them along edge portions of successively presented container body blanks so that as said blanks are formed into containers the packing strips will be positioned in the side seams thereof. An example of a form of container including a packing strip in the solderless side seam is illustrated in U. S. Letters Patent 2,171,711, issued to Walter G. Plumb and Herbert Schrader on September 5, 1939. The present application is a division of my copending application aforesaid.

An object of the invention is to provide in apparatus of the character stated means for detecting the absence of a packing strip on any given successively presented container body blank and for ejecting such defective or incomplete blanks from the apparatus.

Another object of the invention is to provide in apparatus of the character stated in which the body blanks are fed station by station, means located of one station for detecting the absence of a packing strip on a blank presented at said one station, and means at another station controlled by said detecting means for automatically ejecting all blanks detected to be devoid of packing strips.

Another object of the invention is to provide an apparatus of the character stated in which the ejecting means is electrically actuated and the detecting means includes a reciprocable contact member engageable with strip bearing blank edge portions and forming a part of a control circuit normally insulated and broken by the engaged packing strips and completed only by blank metal contact occasioned by an absence of a packing strip from a given blank.

Another object of the invention is to provide an apparatus of the character stated in which the ejecting means includes an actuator slide constantly reciprocated transversely of the direction of feed of the blanks, an ejector slide movable at times with the actuator slide, and

2

latching means carried by one slide and engageable with the other slide to cause the slides to move together only when the detecting means has detected the absence of a packing strip from a blank.

Another object of the invention is to provide in apparatus of the character stated, an ejecting means including a latch position determining means embodying a rotary cam having a dwell portion effective to delay the latching function until a blank detected as being devoid of a packing strip has been moved to the ejecting station.

With the above and other objects in view that will hereinafter appear, the nature of the invention will be more fully understood by following the detailed description, the appended claims and the several views illustrated in the accompanying drawings.

In the drawings:

20 Figure 1 is a fragmentary side elevation illustrating the invention as embodied in a container body making machine.

Figure 2 is a vertical cross section of the machine portion illustrated in Figure 1, the section being taken at the position of the packing strip applying station.

Figure 3 is an enlarged fragmentary vertical cross section taken at the detector station.

30 Figure 4 is an enlarged side elevation illustrating the parts at the detector and blank ejector stations, parts being broken away and in section.

Figure 5 is a fragmentary plan view at the position of the blank ejecting slides, the housing cover being removed and parts being broken away and in section.

Figure 6 is a fragmentary vertical cross section taken on the line 6—6 on Figure 5.

Figure 7 is a cross sectional view taken through the blank ejecting mechanism and the ejected blank receiving housing.

Figure 8 is a fragmentary perspective view of a body blank with a packing applied thereon.

Figure 9 is a diagrammatic view illustrating the relative timing of the blank feeding, detecting and ejecting devices.

In the example of embodiment of the invention herein disclosed the invention is shown as embodied in one section of a container body making machine. This type of machine is well known and an example of such a body maker is disclosed in the U. S. Letters Patent to Troyer et al. 1,772,820, issued August 12, 1930.

In the type of body maker referred to, can body blanks are withdrawn one by one from a supply stack and are fed intermittently, or station to

station, along suitable supporting ways. At one station the blanks are fed from a low level laterally through grain breaking rolls and are returned by these rolls to a higher level along which they are again fed step by step. At another station the lateral edges of the blanks are notched and slit. At another station the edge hooks which are to be interlocked in the formation of a lock and lap seam are bent. At another station the blanks are shaped about a forming horn in a manner for bringing the hooks thereof into interlocking relation, and at this same station a bumping steel engages the hooks and serves to finish the seam.

The herein disclosed first section of the improved body making machine, preferably assembled as an attachment to the remaining standardized and conventional parts of the body making machine, includes a base 5 which may be a separate base extending throughout this particular section of the machine only, or it may be an extension from the base of the main or body forming section of the machine. The attachment includes a bed 6 forming an extension of the bed of the main section of the machine and which is supported on frame legs 1. The bed 6 supports side housing members 8 which form extensions of the like portions of the main section of the machine and are arranged in parallel spaced relation in the usual manner. The housing members 8 support suitable slideways or guides 9, 9a for the lateral edges of the blanks 10 which are fed along the ways step-by-step, or station-by-station, by the conventional reciprocable feed bars 11 in the manner well known to all workers in the art familiar with the so-called 4-B body maker herein referred to. The blanks 10 are fed between the usual upper and lower center guide members 12. See Figures 1 and 2.

The machine attachment frame supports a blank stack 13 from which blanks are individually withdrawn from the bottom in the usual manner by a suction cup 14 mounted at the upper end of a vertically reciprocable carrier 15 which is crank and link connected as at 16 with a thrust arm 17 in turn connected with a crank 18 driven by power transmitting connections 19 from the power shaft 20. The power shaft 20 has bearings as at 21 in the gear housing 22 and is coupled as at 23 with the main power shaft 24 having bearing as at 25 in the gear housing 26. See Figure 1.

Within the gear housing 26, the main power shaft 24 is coupled in driving relation as at 27 with two cam shafts 28 and 29, the cam shaft 28 forming a part of the attachment herein disclosed and the shaft 29 being a part of the standard body maker or the main body forming section of the composite machine herein referred to. The shafts 28 and 29 rotate in suitable bearings 30 supported on the machine framing. See Figure 1.

The machine attachment includes a blank grain breaking station generally designated 31 at which each blank fed from the stack is fed laterally through grain breaking rolls and is again returned laterally onto the blank feedways at a higher level, the blank shifting means being generally designated 32 and being driven by power transmitting connections 33 from the cam shaft 28. At the blank rolling or grain breaking station each blank is stopped or registered by a rockably mounted stop member 34 which functions in a well known manner and has movement imparted thereto, for the purpose of alternately moving into position for intercepting blanks and then moving away, by cam and roller

equipment generally designated 35. After leaving the grain breaking station 31 each blank is fed to an idle station generally designated 36, and at the next feed step is delivered at the packing strip applying station generally designated 37. Another idle station 38 follows the strip applying station, and the next step station, generally designated 39, is in the nature of a packing strip absence detecting station which is immediately followed by a station generally designated 40 at which all blanks which are found not to have a packing strip applied thereto are ejected. The detecting and blank ejecting mechanisms mounted at 39 and 40 are the mechanisms with which the present invention is principally concerned. See Figure 1.

At the packing strip applying station there is mounted a web supply roll 41 of packing strip material. The web 42 of packing strip material 20 has a heat fusible adhesive coating on its under face and is fed step-by-step through constantly driven draw rolls 43 and over an intermittently driven drag feed roll 44 so as to expose packing strip lengths thereof successively over the die block 45. As each packing strip length is exposed over the die block it is severed by a packing strip forming, carrying and applying plunger 46 radially reciprocably mounted in the rotor 47, a plurality of such plungers being carried by the rotor as shown in Figure 2. Each plunger has means for pneumatically holding a formed packing strip thereon and the rotor is indexed to carry the packing strips through a heating zone in which the adhesive thereon is rendered tacky and to the applying position directly under the longitudinal center of the rotor whereat the plunger is projected as indicated in Figure 2 to apply the strip to the side edge of the body blank 10 then presented at the applying station. The strip heating means is indicated at 48, and the rotor indexing means, the plunger projecting and retracting means, and the pneumatic control means all are disclosed in detail and covered in my copending application for U. S. Letters Patent, Serial Number 371,974, filed December 27, 1940, now Patent No. 2,319,825, issued May 25, 1943, of which the present application is a division. One of the applied packing strips is indicated at 49 in Figure 8.

Obviously, should any body blanks be fed through the machine and not have a packing strip affixed thereto, such blanks would be formed into cans which would leak at the side seams. Such cans would have to be destroyed because it would be impractical to attempt salvaging thereof. It is the purpose of the present invention to prevent this waste by providing novel means for detecting blanks devoid of packing and ejecting them from the feed line so that they will not be made into cans and can be again fed through the machine or otherwise used.

The station immediately following the packing strip applying station is an idle station 38 as hereinbefore described. The detecting mechanisms are positioned at the next succeeding station designated 39, and the blank ejecting means is located at the following station which is generally designated 40. At the detecting station a special bracket 50 is mounted and this bracket supports a rock shaft 51. See Figures 1, 3, and 4. The rock shaft rockably supports a bell crank lever 52 which carries the conventional blank edge clamping and stopping equipment generally designated 53 and which includes an actuator roller engaged by an actuator cam 54 secured

upon the shaft 28. The bracket 50 also supports a shaft 55 which rockably mounts a bell crank lever 56, one arm of which carries a roller engaged by a detector cam 57 secured upon the shaft 28, and the other arm 58 of which is normally forced upwardly so as to hold the roller against the cam by a spring plunger 59 carried by the bracket. The arm 58 removably supports a detector unit comprising a base block 60 formed of insulating material on which is mounted a bearing member 61. See Figure 3. A detector or conductor bar 62 is pivotally supported intermediate of its ends on the bearing member 61 in position for having one end thereof overlie the edge portion of a blank presented at this station. This overlying end portion of the conductor bar 62 carries a depending detector pin 63. The portion of the container body blank opposed by the detector pin 63 rests upon a supporting rail 64 which is suitably grounded as a part of the electrical detecting and ejecting control circuit. Movement of the detector pin toward the rail 64 is limited by an adjustable stop screw 65 which can be accurately adjusted to permit the pin 63 to move downwardly far enough to engage a blank edge portion devoid of a packing strip but not far enough to engage the supporting rail 64. The other end of the contact bar is lifted by a spring plunger 66, and this contact bar is connected in the control circuit by a screw 67 which serves as an attaching medium for the conducting wire 68. It will be obvious that during each rotation of the cam 57 the detector pin 63 will be moved into and then out of contact with the particular container body blank presented at the detecting station.

The ejecting mechanism located at station 40 includes a housing 69 having a removable cover and mounted as at 70 on the left side housing member 8. See Figures 1, 4, 6 and 7. Within the housing a slide member 71 is constantly reciprocable transversely of the direction of feed of the blanks in a slide guideway 72, said slide being link-connected as at 73 with the upper end of a rock member 74 pivotally supported as at 75 and having its lower end equipped with an actuator roller engaged by an actuator cam 76 mounted on the shaft 28. An ejector slide 77 is slidably mounted above the slide 71 in a guideway 78, and this ejector slide moves with the slide 71 only when the latch 79 carried thereby is depressed into the path of movement of and contacts the actuator plate portion 80 carried by the slide 71, said plate 80 having a recess 81 therein for receiving the end of said latch. See Figures 4, 6 and 7.

The latch member 79 carries a depresser roller 82 projecting from the top of the latching end thereof, and a spring 83 normally holds the latch lever in the lifted or unlatched position determined by the stop 84 formed by the projected opposite end of said latch member. The slide 71 has an opening 85 therein through which the latch 79 projects and also carries an ejector plate 86 removably secured to the end thereof and including a notched end portion 87 for normally underlying the side edge portion of a blank presented at the ejecting station.

Whenever the ejector slide 77 is latch-connected to the actuator slide 71, the blank presented at the ejecting station will be engaged by the notched end portion 87 of the slide and moved laterally far enough to be presented between constantly rotating ejector rolls 88 which will serve to eject the blank from the feedways.

As each ejector blank is being moved through the rolls 88 it is caused to pass between a straightening roll 89 and an opposing steel 90 and thence into the ejector blank receiving magazine 91.

- 6 The roll and steel equipment 89 and 90 serve to remove from the blank the tendency to bend imparted thereto by the rolls at the grain breaking station hereinbefore referred to, and while the blank being ejected is moving through the 10 rolls 88, the overlying guide member 92 disposed at the ejecting station prevents upward buckling of the blank.

The means for bringing about a latching of the ejector slide with the actuator slide under control of the detector mechanism will now be described.

- 15 A solenoid 93 is mounted in the housing 69 and is connected with a suitable source of power diagrammatically illustrated at 94 which also connects with the conductor line 68 connected with the contact bar 62 in the manner hereinbefore described. The solenoid is also grounded, and thus a control circuit is completed whenever the detector pin 63 engages the bare metal of a blank devoid of a packing strip at the 20 detecting station, said circuit being completed through the ground connection of the rail 64, the metal blank 10, the detector pin 63, the conductor bar 62, the conductor 68, the power source 94, and the ground connection of the solenoid. See 25 Figures 4 and 5.

- 30 Whenever the solenoid is energized by completion of the circuit in the manner just above described, the core 95 of the solenoid is retracted against the compression spring 96 which engages 35 a latch lever 97 to which the core is link-connected as at 98. The spring normally holds the latch member 97 against an adjustable stop 99. The latch member 97 includes an undercut nose portion 100 engageable by a latch nose 101 removably attached to the upper end of a vertically reciprocable member 102 which carries a roller at its lower end and is yieldably held against an actuator cam 103 secured upon the cam shaft 28'. It will be obvious that the latch nose 101 is constantly reciprocated and also that it will engage the undercut nose portion 100 of the latch member 97 only when said latch member is moved into the path of travel thereof by retraction of the solenoid core in the manner illustrated in 50 Figure 4 of the drawings.

- 55 The latch member 97 is pivotally mounted on a rocker member 104 fulcrumed intermediate of its ends as at 105, and it will be observed that the solenoid also is secured to this rocker member as at 106. A compression spring 107 normally serves to lift the end which carries the latch member 97, an adjustable stop screw 108 serving to determine the normal position of said rocker member.

- 60 The spring lifted end of the rocked member carries a pivotally mounted actuator finger 109 which is yieldably depressed by a compression spring 110 and which overlies the latch depressing roller 82 carried by the latch member 79. Thus each time the solenoid is energized the latch member 97 is moved over into the path of vertical reciprocation of the nose 101 and upward movement of said nose will serve to lift the end of the rocker member 104 to which the latch member 97 is attached and depress the end of said rocker member which carries the depresser finger 109, and it will be obvious that depression of the member 109 will serve to depress the latch member 79 into position for being engaged by the actuator 70 75

slide thereby to cause the slides 71 and 71 to move together and effect an injection of a blank in the manner hereinbefore described.

It will be obvious that as a blank detected as being devoid of a packing strip at the detecting station is moved from that station 39 to the ejecting station 40 it will move out of contact with the detector pin 63 and break the solenoid circuit effective to retract the core 95 and initially position the latch member 97 in the position illustrated in Figure 4. Were no means provided for retaining this initial position of the latch member 97 while the blank is being moved to the ejecting station, the rocker member 104 would not be properly actuated to effect latching of the slide 71 and 71 in the manner hereinbefore described. In order to provide for the delayed action necessary to permit shifting of the blanks from the detecting station subsequent to the closing of the control circuit at the detecting station and prior to latching of the slides at the ejector station, the cam 103 is provided with a dwell for holding the latch nose 101 in the position illustrated in Figure 4 during the delay interval stated. This cam includes an additional rise portion effective after the delay interval referred to to additionally lift the nose 101, the latch member 97 and the rocker member 104 for effecting depression of the finger 109 and the underlying latch member 79. During the delay interval referred to, the latch 97 is held in engagement with the partially lifted nose 101 by reason of the undercut 100 despite the fact that the solenoid energizing circuit has been broken.

In Figure 9 of the drawings there is shown a chart or diagram illustrating the relative timing of the blank feeding, detecting and ejecting devices in which the vertical lines indicate units of time, or distance travelled, and the lines traversing said vertical lines in generally horizontal direction indicate the relative timing of the various mechanisms. The uppermost line indicates the timing of the sheet or blank feeding devices. The second generally horizontal line, reading downwardly, indicates the timing of the cam 57 which operates the detector pin 63 (see Figure 3). The next horizontal line indicates the relative timing of the energizing of the solenoid 93 which is energized when the detector pin makes electrical contact with a blank devoid of a packing strip. The next or fourth generally horizontal line indicates the relative timing of the cam 103 which operates the latch nose 101 shown in Figure 4. The next or 5th generally horizontal line indicates the relative timing of the cam 76 which operates the ejection slide (see Figure 6). The lowermost or sixth generally horizontal line indicates the relative timing of the blank ejecting action of the ejector rolls 88 and 89.

The lever 74 is held against the cam 76 by a spring projected sleeve 111 supported on the pivotally mounted pin 112.

It is, of course, to be understood that the details of structure and the arrangement of parts may be variously changed and modified without departing from the spirit and scope of the invention.

I claim:

1. In apparatus of the character described, longitudinally extended body blank supporting ways, means for feeding body blanks having side seam packing strips affixed thereon step-by-step along said ways so as to present them at rest intervals at a succession of stations, means operable at one rest interval stop station on said ways and

while a blank is at rest at said stop station for detecting the absence of a packing strip on said blank, and blank moving means controlled by said detecting means and operable for automatically imparting movement of ejection to each blank found devoid of a packing strip.

2. In apparatus of the character described, body blank supporting ways, step-by-step feed means for feeding station-by-station along said ways body blanks having side seam packing strips affixed thereon, means at one stop station movable into and out of engagement with blanks stationary at said stop station and at the position on said blanks customarily occupied by the packing strips thereon for detecting presence or absence of packing strips, and blank moving means disposed at another stop station and controlled by said detecting means for automatically engaging and imparting movement of ejection to each blank coming to rest at said another stop station after having been detected to be devoid of a packing strip.

3. In apparatus of the character described, body blank supporting ways, step-by-step feed means for feeding station-by-station along said ways body blanks having side seam packing strips affixed thereon, means at one stop station movable into and out of engagement with blanks stationary at said stop station and at the position on said blanks customarily occupied by the packing strips thereon for detecting presence or absence of packing strips, and blank moving means controlled by said detecting means and operable at a stop station during a rest interval of the blank feed for automatically engaging and imparting movement of ejection to each blank detected to be devoid of a packing strip.

4. In apparatus of the character described, body blank supporting ways, step-by-step feed means for feeding station-by-station along said ways body blanks having side seam packing strips affixed thereon, means at one stop station movable into and out of engagement with blanks stationary at said stop station and at the position on said blanks customarily occupied by the packing strips thereon for detecting presence or absence of packing strips, blank moving means controlled by said detecting means and operable at a stop station during a rest interval of the blank feed for automatically engaging and imparting movement of ejection to each blank detected to be devoid of a packing strip, and means for deferring each action of the ejecting means so that each ejecting action will take place at a station other than that at which the detecting occurs.

5. In apparatus of the character described, body blank supporting ways, step-by-step feed means for feeding station-by-station along said ways body blanks having side seam packing strips affixed thereon, means at one stop station movable into and out of engagement with blanks stationary at said stop station and at the position on said blanks customarily occupied by the packing strips thereon for detecting presence or absence of packing strips, blank moving means controlled by said detecting means and operable at a stop station during a rest interval of the blank feed for automatically ejecting each blank detected to be devoid of a packing strip, and cam controlled means for deferring each action of the ejecting means so that each ejecting action will take place at a station other than that at which the detecting occurs.

6. In apparatus of the character described, body blank supporting ways, means for feeding

along said ways body blanks having side seam packing strips affixed thereon, means for detecting the absence of a packing strip on a blank, and means controlled by said detecting means for automatically ejecting all blanks devoid of packing strips, said last named means including an actuator slide constantly reciprocated transversely of the direction of feed of said blanks, ejecting rolls, a blank ejecting slide movable at times with the actuator slide for presenting blanks to said ejecting rolls, and latching means carried by one slide and engageable with the other slide to cause the slides to move together only when said detecting means has detected the absence of a packing strip on a blank.

7. In apparatus of the character described, body blank supporting ways, means for feeding station-by-station along said ways body blanks having side seam packing strips affixed thereon, means at one station movable into and out of engagement with blanks at the position customarily occupied by the packing strips thereon for detecting presence or absence of packing strips, and means at another station controlled by said detecting means for automatically ejecting all blanks detected to be devoid of packing strips, said last named means including an actuator slide constantly reciprocated transversely of the direction of feed of said blanks, ejecting rolls, a blank ejecting slide movable at times with the actuator slide for presenting blanks to said ejecting rolls, and latching means carried by one slide and engageable with the other slide to cause the slides to move together only when said detecting means has detected the absence of a packing strip on a blank.

8. In apparatus of the character described, body blank supporting ways, means for feeding station-by-station along said ways body blanks having side seam packing strips affixed thereon, means at one station movable into and out of engagement with blanks at the position customarily occupied by the packing strips thereon for detecting presence or absence of packing strips, and means controlled by said detecting means for automatically ejecting all blanks detected to be devoid of packing strips, said last named means including an actuator slide constantly reciprocated transversely of the direction of feed of said blanks, ejecting rolls, a blank ejecting slide movable at times with the actuator slide for presenting blanks to said ejecting rolls, and latching means carried by one slide and engageable with the other slide to cause the slides to move together only when said detecting means has detected the absence of a packing strip on a blank, and means for deferring each action of the ejecting means so that each ejecting action will take place at a station other than that at which the detecting occurs.

9. In apparatus of the character described, body blank supporting ways, means for feeding station-by-station along said ways body blanks having side seam packing strips affixed thereon, means at one station movable into and out of engagement with blanks at the position customarily occupied by the packing strips thereon for detecting presence or absence of packing strips, and means controlled by said detecting means for automatically ejecting all blanks detected to be devoid of packing strips, said last named means including an actuator slide constantly reciprocated transversely of the direction of feed of said blanks, ejecting rolls, a blank ejecting slide movable at times with the actuator

slide for presenting blanks to said ejecting rolls, latching means carried by one slide and engageable with the other slide to cause the slides to move together only when said detecting means has detected the absence of a packing strip on a blank, and cam controlled means for deferring each action of the ejecting means so that each ejecting action will take place at a station other than that at which the detecting occurs.

10. In apparatus of the character described, body blank supporting ways, means for feeding station-by-station along said ways body blanks having side seam packing strips affixed thereon, means at one station movable into and out of engagement with blanks at the position customarily occupied by the packing strips thereon for detecting presence or absence of packing strips, means at another station controlled by said detecting means for automatically ejecting all blanks detected to be devoid of packing strips, said last named means including an actuator slide constantly reciprocated transversely of the direction of feed of said blanks, ejecting rolls, a blank ejecting slide movable at times with the actuator slide for presenting blanks to said ejecting rolls, latching means carried by one slide and engageable with the other slide to cause the slides to move together only when said detecting means has detected the absence of a packing strip on a blank, said detecting means including a contact member engageable with the blanks at the position customarily occupied by the packing strips and forming a part of a control circuit normally insulated and broken by the engaged packing strips and completed only by blank metal contact occasioned by absence of a packing strip on a given blank, and said ejecting means including a latch position determining solenoid energized or deenergized by the completing or breaking of said control circuit.
11. In apparatus of the character described, body blank supporting ways, means for feeding station-by-station along said ways body blanks having side seam packing strips affixed thereon, means at one station movable into and out of engagement with blanks at the position customarily occupied by the packing strips thereon for detecting presence or absence of packing strips, and means at another station controlled by said detecting means for automatically ejecting all blanks detected to be devoid of packing strips, said last named means including an actuator slide constantly reciprocated transversely of the direction of feed of said blanks, ejecting rolls, a blank ejecting slide movable at times with the actuator slide for presenting blanks to said ejecting rolls, latching means carried by one slide and engageable with the other slide to cause the slides to move together only when said detecting means has detected the absence of a packing strip on a blank, and a latch position determining means including a rotary cam having a dwell portion effective to delay the latching function until the blank detected as being devoid of a packing strip has been moved to the ejecting station.

12. In apparatus of the character described, body blank supporting ways, means for feeding metallic blanks having side seam packing strips affixed thereon longitudinally along said ways, and electrically controlled blank moving means for ejecting laterally from said ways all blanks having no packing strips affixed thereon, said last named means including a reciprocable ejector slide, a detector contact en-

11

gageable with the blanks at the position on said blanks customarily occupied by the packing strips, and an electrical control circuit and control means active each time said contact touches the bare metal of a blank indicating the absence of a packing strip therefrom for rendering said slide effective to push laterally the blank devoid of a packing strip.

13. In apparatus of the character described, body blank supporting ways, means for feeding metallic blanks having side seam packing strips affixed thereon longitudinally along said ways, and electrically controlled means for ejecting laterally from said ways all blanks having no packing strips affixed thereon, said last named means including a constantly reciprocated slide actuator, a transversely reciprocable ejector slide, a detector contact engageable with the blanks at the position on said blanks customarily occupied by the packing strips, and an electrical control circuit and control means active each time said contact touches the bare metal of a blank indicating the absence of a packing strip therefrom for effecting a coupling of the slide and actuator to cause the slide to push laterally the blank devoid of a packing strip.

14. In apparatus of the character described, body blank supporting ways, means for feeding metallic blanks having side seam packing strips affixed thereon longitudinally along said ways, and electrically controlled blank moving means for ejecting laterally from said ways all blanks having no packing strips affixed thereon, said last named means including a transversely reciprocable ejector slide, a detector contact engageable with the blanks at the position on said blanks customarily occupied by the packing strips, and an electrical control circuit and control means active each time said contact touches the bare metal of a blank indicating the absence of a packing strip therefrom for rendering said slide effective to push laterally the blank devoid of a packing strip, and a pair of ejector rolls for receiving the blank devoid of a packing strip from said slide and completing the ejection thereof.

15. In apparatus of the character described, body blank supporting ways, means for feeding metallic blanks having side seam packing strips affixed thereon longitudinally along said ways, and electrically controlled means for ejecting laterally from said ways all blanks having no packing strips affixed thereon, said last named means including a transversely reciprocable ejector slide, a detector contact engageable with the blanks at the position on said blanks customarily occupied by the packing strips, and an electrical control circuit and control means active each time said contact touches the bare metal of a blank indicating the absence of a packing strip therefrom for rendering said slide effective to push laterally the blank devoid of a packing strip, and a pair of ejector rolls for receiving the blank devoid of a packing strip from said slide and completing the ejection thereof, and means cooperating with said rolls in working the grain in ejected blanks so as to cause said ejected blanks to lie flat.

12

in ejected blanks so as to cause said ejected blanks to lie flat.

16. In apparatus of the character described, body blank supporting ways, means for feeding metallic blanks having side seam packing strips affixed thereon longitudinally along said ways, and electrically controlled means for ejecting laterally from said ways all blanks having no packing strips affixed thereon, said last named means including a constantly reciprocated slide actuator, a transversely reciprocable ejector slide, a detector contact engageable with the blanks at the position on said blanks customarily occupied by the packing strips, and an electrical control circuit and control means active each time said contact touches the bare metal of a blank indicating the absence of a packing strip therefrom for effecting a coupling of the slide and actuator to cause the slide to push laterally the blank devoid of a packing strip, and a pair of ejector rolls for receiving the blank devoid of a packing strip from said slide and completing the ejection thereof.

17. In apparatus of the character described, body blank supporting ways, means for feeding metallic blanks having side seam packing strips affixed thereon longitudinally along said ways, and electrically controlled means for ejecting laterally from said ways all blanks having no packing strips affixed thereon, said last named means including a constantly reciprocated slide actuator, a transversely reciprocable ejector slide, a detector contact engageable with the blanks at the position on said blanks customarily occupied by the packing strips, and an electrical control circuit and control means active each time said contact touches the bare metal of a blank indicating the absence of a packing strip therefrom for effecting a coupling of the slide and actuator to cause the slide to push laterally the blank devoid of a packing strip, and a pair of ejector rolls for receiving the blank devoid of a packing strip from said slide and completing the ejection thereof, and means cooperating with said rolls in working the grain in ejected blanks so as to cause said ejected blanks to lie flat.

PAUL E. PEARSON.
